ATTORNEY

UNITED STATES PATENT OFFICE.

HENRY MATHIS, OF VIRGINIA, MINNESOTA.

CHAIN-REPAIR TOOL.

1,398,876.

Specification of Letters Patent. Patented Nov. 29, 1921.

Application filed December 18, 1920. Serial No. 431,660.

To all whom it may concern:

Be it known that I, HENRY MATHIS, a citizen of the United States, residing at Virginia, in the county of St. Louis and State 5 of Minnesota, have invented new and useful Improvements in Chain-Repair Tools, of which the following is a specification.

This invention relates to tools and more particularly to a tool designed to facilitate 10 the repairing of anti-skid chains as used upon motor vehicle wheels.

An object of the invention is to provide 15 a tool by means of which repairs may be made to an anti-skid chain quickly and easily, on the road, or in a garage. The said tool embodies a pivotal jaw member co-acting 20 with a rigid handle carried jaw member each of which carry link spreading points by means of which the connecting link-eyes 25 may be spread, and which also comprise roughened gripping jaws for closing the eyes 30 of the connecting links of the jaw.

A further object of this invention is to provide a tool constructed whereby spreading 25 or closing of the connecting eyes of chain links is provided by a pivotal hand lever, having a cam thereon arranged to increase the leverage of the pivotal hand lever to make it comparatively easy to spread or 30 close the link eyes.

Other objects of the invention will appear in the following detailed description and in the accompanying drawings wherein:

Figure 1 is a perspective of the improved 35 tool.

Fig. 2 is a detailed side elevation of the improved tool having one of its side plates removed.

Fig. 3 is an end view of the tool.

Referring more particularly to the drawings, the improved tool comprises a handle 1, to which side plates 2 and 3 are detachably connected. The side plates 2 and 3 pivotally support a second hand lever 4 upon the 45 inner edge of the pivoted end of which lever a cam projection 5 is formed. The cam projection 5 engages one edge of the pivotal jaw 6 pivotally connected as shown at 7 to the side plates 2 and 3.

The free end of the jaw 6 projects beyond 50 the side plates 2 and 3 and is offset laterally as shown at 8 in Figs. 1 and 3 of the drawings. The lateral offset end of the jaw 6 has an eye spreading point or head 9 formed 55 thereon to coact with the eye spreading

point or head 10 which is formed upon the laterally offset end 11 of the handle 1.

As clearly shown in Fig. 3 of the drawings, the inner engaging surfaces of these heads 9 and 10 are flat and are in parallelism 60 while their outer surfaces are rounded and tapered to extend into the connecting eyes of links of anti-skid tire chains.

The jaw 6 is urged outwardly from the handle 1 and against the convex edge of the cam projection 5 by a flat spring 12 which is connected to the said plates 2 and 3 by a pin 12'. The handle 1 is provided with arcuate projections 13 and 14 on its inner edge which engage the flat spring 12 and 70 maintain the spring in proper tensioned position to impart the necessary urging action to the jaw 6.

The jaw 6 and the handle or hand lever 1 are provided with roughened surfaces 15 75 and 16 respectively on their facing edges adjacent their lateral projecting ends, and these roughened places are adapted for engagement with the connecting eyes of the links of a chain for closing the links. 80

The handle of hand lever 4 is arcuately curved between its pivotal and free end as shown at 17 to permit the hand gripping portion thereof to extend parallel to and in engagement with the facing edge of the 85 handle or hand lever 1 when the jaw 6 is forced into a closed position by the cam projection 5 as shown in solid lines in Fig. 2 of the drawings.

Owing to the curvature of the cam projection 5, the urging action of the spring will force the jaw 6 and hand lever 4 outwardly into an extended or open position as shown in dotted lines in Fig. 2 of the drawings. However, this curve or convex edge 90 of the cam projection is formed so that when the jaws are closed they will be held closed and the handle 4 must be moved a short distance relatively to the handle 1 to release the jaw 6 for opening action by the spring 12. 95 Relatively long leverage is provided in the tool, which makes it very easy to operate, by the relative lengths of the handle 4, and of the maximum radius of the cam projection 5. 100

A clip 20 is provided having lateral attaching flanges 21 to permit the clip to be attached to a work bench, and when it is desired to work or operate the improved tool by one hand, the handle 1 is slipped under 110

the up-standing U shaped portion 22 of the clip 20 as shown in Fig. 1 of the drawings.

It is, of course, to be understood that the invention may be constructed in various other manners, and the parts associated in different relations and, therefore, I do not desire to be limited in any manner except as set forth in the claim hereunto appended.

Having thus described my invention what

10 I claim is:

A tire-chain repair tool comprising a handle having one end laterally offset, a spreading point formed on and extending laterally inward at right angles to the extremity of said laterally offset end plates spaced apart and fixed to said handle and extending beyond one edge thereof, a jaw 15 pivotally mounted between said plates and having a laterally offset end, a spreading

point on and extending laterally inward at right angles to the extremity of said laterally offset end for co-operation with the spreading point on said handle; the said points having inner flat sides in closely adjacent parallel planes and also having outer sides tapered to points and the said points being reversely directed, a lever pivoted between the said plates at a point forwardly beyond and outwardly from the center of movement of the jaw and having at its forward end a rounded cam projection opposed to the outer edge of the jaw, and a spring interposed between the handle and the inner edge of the jaw and tending to force the jaw outwardly.

35 In testimony whereof I affix my signature.

HENRY MATHIS.
